UNITED STATES PATENT OFFICE.

THOMAS P. SHEAN, OF CHICAGO, ILLINOIS.

METAL WINDOW CONSTRUCTION.

Application filed February 1, 1926. Serial No. 85,095.

The present invention relates to metallic window constructions, and is particularly concerned with improvements in such parts thereof as the muntin bars, the sash guides, 5 the cord pulleys, the weight pockets, and other of the structural elements.

One object of the invention is to provide, in a metallic window construction, an improved muntin bar which is light, strong and 10 durable in character, may be fabricated at small expense with the use of very simple equipment, is capable of being easily glazed, and requires only a very thin layer of putty in the glazing operation.

15 Another object is to provide an improved sash guide which is extremely simple in character, will cooperate with both the upper and lower sashes in a double-hung window, and affords an efficient weather 20 closure for the margins of the sashes when the latter are in closed positions.

Another object is to provide an improved mounting for the cord pulleys, whereby the 25 pulleys are rendered readily accessible for replacement, adjustment, or repair.

A further object is to provide an improved closure for the weight pockets, whereby the weights may be withdrawn to 30 permit the removal of worn cords and the attachment of new ones.

The foregoing statements are but indicative in a general way of the nature of the invention, and other objects and advantages connected with various features of the window 35 will be evident to those skilled in the art upon a full understanding of the novel construction and arrangement of parts herein illustrated and described.

One form of the invention is presented 40 for the purpose of exemplification, but it should be understood that the invention is not confined in its practical application to the precise structural details of that form, as such details quite obviously may be modified in various respects without departing 45 from within the comprehensive scope of the invention as defined by the claims.

In the drawings:

50 Fig. 1 is a front elevation of a window embodying the several features of the invention;

Fig. 2 is a horizontal section through the window, taken on the line 2—2 of Fig. 1;

55 Fig. 3 is a vertical section through the window, taken on the line 3—3 of Fig. 1;

Fig. 4 is a vertical section through a muntin bar in one of the sashes, taken on the line 4—4 of Fig. 2;

Fig. 5 is a vertical section through a weight pocket cover in one of the jambs, 60 taken on the line 5—5 of Fig. 2;

Fig. 6 is a vertical section through the sill near one of the jambs, the lower sash being raised in order to show the arrangement of one of the sash guides with respect 65 to the sill;

Fig. 7 is a top plan view of one of the upper corners of the frame, showing the mounting of the cord pulleys;

Fig. 8 is a vertical section through the 70 pulley mounting, taken on the line 8—8 of Fig. 7; and

Fig. 9 is a horizontal section through one 75 of the sash guides, taken on the line 9—9 of Fig. 3.

The metallic window construction illustrated in the drawings is of the double-hung sash type, as certain, though not all, of the features of the invention are particularly applicable to windows of that type. 80

The frame of the window is composed of four permanently connected sheet metal channel members 10, 11, 12 and 13, which members are so arranged that the bases of the channels therein serve to form the inner 85 periphery of the frame.

The sill member 10 is provided with two vertically and horizontally offset wall portions 14 and 15 which are positioned in approximately the front and rear bounding 90 planes of the lower sash in order to present seats against which the similarly offset edges of the sides 16 and 17 of the lower rail 18 of such sash are adapted to fit. The portion of the sill member in front of the wall 95 portion 15 is arranged at a slight forward inclination, as is usual in sill formations.

The lintel member 11 is provided with a groove 19 which is positioned with its sides 20 and 21 in the planes of the upper sash in 100 order to receive the edges 22 and 23 of the upper rail 24 of such sash. One of the sides of the groove is preferably set at a slight angle to the bounding planes of the upper sash so as to obtain a wedging fit of the rail 24 in the groove. 105

Each of the two jamb members 12 and 13 is provided with a wall portion 25 against which the front edge 26 of the stile 27 of the upper sash is adapted to fit. The jamb ex- 110

tends rearwardly from the wall portion 25 in a flat surface.

The openings in the channels of the lintel and jamb members are preferably closed off from the surrounding masonry of the building in which the window is installed by relatively thin sheet metal strips 28 which are attached to the edges of the members. The opening in the sill member is not closed off, but the member may be provided with a downwardly flanged sheet metal strip 29 which is adapted to extend into a groove in the sill of the supporting masonry, where it serves as a water bar.

15 The rails and stiles of the upper and lower sashes are of hollow sheet metal formation, and the margins of the glass panes 30 extend into relatively small putty grooves which are formed in the rails and stiles by U-shaped strips 31 which are fixedly positioned therein. The strips 31 in the top rails may be of greater vertical extent than those in the bottom rails in order that, when the sashes are being glazed, the glass panes 30 may be 20 raised upwardly in the upper grooves a sufficient distance to permit the lower margins of the panes to first clear the upper margins of the bottom rails and then seat in the grooves therein, which arrangement makes 25 possible a permanent assemblage of the structural elements constituting the rails and stiles.

In the lower sash, the bottom rail 18 is composed of two parallel side strips 32 35 which are held in fixed relation by two connecting strips 33. The associated glass-retaining strip 31 is anchored to the uppermost strip 33, and the upper margins of the side strips 32 are curved toward each other 40 over the edges of the strip 31. The top rail 34 is composed of two parallel side strips 35 which are perpendicularly flanged in one direction and secured together in front of the sash at 36, one of the flanged portions being 45 provided in front of the sash with a downwardly extending flange 37 which is adapted, when both the upper and lower sashes are in closed positions, to imbed in a weather strip 38 of felt or other suitable material carried in a groove formed in the bottom rail 39 of the other sash. The stiles 40 are quite 50 similar in construction to the bottom rail 18, the principal differences being that the side strips 41 are of equal instead of unequal width, and that but one connecting strip 33 is used between the side strips owing to the fact that the stiles are less elongated in cross section than the rail.

In the upper sash, the bottom rail 39 is 55 composed of a front side strip 42 which is flanged rearwardly at its lower margin and then upwardly to form the rear side of the groove in which the weather strip 38 is located, and a rear side strip 43 which is secured to the strip 39 in such a way as to

form a small putty groove for the lower margin of the glass pane 30 and a relatively large hollow box rail extending rearwardly from the putty groove to a point closely adjacent the front flange 37 on the top rail 34 70 of the lower sash. The top rail 24 is composed of two parallel side strips 44 which are held in fixed relation by a connecting strip 45 which also serves to reinforce the upper edges 22 and 23 of the rail. The stiles 46 75 are substantially the same in construction as the stiles 27 of the lower sash.

Each of the muntin bars 47 of the sashes is composed of two channel strips 48 of curved cross section, one of the strips being fixedly connected at its ends with the associated rails, and the other being detachably secured to the fixed strip. The channel in the fixed strip is closed at a point just inwardly of its edges with a flat strip 49 from which 80 tongues 50 are punched out at intervals and seat against the back of the strip, where they are welded in position. The channel in the detachable strip is also closed in the same manner, but the strip 51 used may be of considerably thinner gauge. The detachable strip is secured to the fixed strip by means of screws 52 which extend through apertures in the strips 48 and 51 and engage in screw-threaded apertures in the strip 49. The construction described is light, is strong, 85 may be easily produced, and requires but a very thin layer of putty between the glass and the strips 49 and 50 in the glazing operation.

The upper and lower sashes are slidably mounted in two oppositely disposed sash guiding strips 53, which are attached by screws 54 to the jambs 12 and 13 of the frame. Each of the guide strips 53 extends 105 the full height of the associated jamb and occupies the space on the jamb between the rear plane of the upper sash and the front plane of the lower sash. The strips are of a triple channel formation in which relatively wide middle channels 55 face toward the jambs and relatively narrow side channels 56 face toward the openings in such channels, and are sufficiently resilient to bear 110 with spring pressure against the edges of the sashes which the channels 56 are adapted to receive. The rear edges of the stiles 46 of the upper sash are guided in the front side channels 56 of the guide strips, and the front edges of the stiles 41 of the lower sash are guided in the rear side channels. The back portions of the middle channels 55 in the guide strips are slightly concave toward the sashes, which construction eliminates the necessity of counter-sinking the attaching screws 54 in the metal of the strips. At that point where the top rail 34 of the lower sash is positioned alongside the bottom rail 39 of the upper sash when both sashes are in closed position, a boss 57 is formed on the 115 120 125 130

back of the middle channel 55 in each of the 5 guide strips by the elimination at that point of the concave formation described, and such boss fits closely against the ends 58 of those portions of the rails 34 and 39 which extend toward each other in hooked relation between the adjacent faces of the sashes, whereby to produce at such point an effective closure between the corners of the sashes and 10 the guide strips when the sashes are closed.

The lower sash is limited in its upward movement by two stop blocks 59 which are positioned in the upper ends of the rear side channels 56 in the guide strips 53. The 15 lower front edge of the bottom rail 18 of the lower sash is wedged closely against the wall portion 15 of the sill when the sash is in its closed position, the wedging action being effected by notching the lower ends of the 20 guide strips at 60, as shown in Fig. 6, and placing the strips in slightly lapped relation to the wall portion 15 so as to present constricted but resiliently yieldable guide 25 grooves 61 at those points in the strips adjacent the sill. A wedge block 62 may also be used at a point on the sill intermediate the guide strips to supplement the wedging action of the lower ends of such strips. The 30 guide construction above described is claimed in my copending application, Serial No. 150,785, filed November 26, 1926.

The pulleys 63 over which the weight cords for the sashes are trained are positioned in the upper corners of the hollow frame, 35 and are journaled in supporting brackets 64. The brackets 64 are flattened on one face, and are arranged in small apertures 65 cut in the jambs 12 at the corners with the flattened faces of the brackets flush with the faces of 40 the jambs. The pulleys and brackets are arranged in pairs in the corners of the frame, and the two brackets of each pair are secured with screws 66 to a common backing plate 67. The plate 67 extends below the 45 brackets 64, and is attached by screws 68 to the jamb 12. The upper end of the plate 67 is provided with an angle member 69 which seats in the base of the channel in the lintel member 11 and is attached thereto by 50 a screw 70. The pulley mounting described properly positions the pulleys, and renders them easily removable. If it is desired for any reason to replace one of the pulleys, the screw 70 is withdrawn, the screw 68 is 55 loosened to permit the plate 67 with the pulley brackets 64 thereon to tilt back into the cavity, the pulley is held while the screw 66 is removed, and the pulley and bracket, being detached from the plate, are withdrawn 60 through the enlarged opening made when the plate 67 was tilted back. A new pulley is then substituted, the backing plate 67 is drawn up into place with the screw 68, and the screw 70 is inserted. The pulley mount- 65 ing above described is claimed in my co-

pending application, Serial No. 150,784, filed November 26, 1926.

The weights 71 for counter-balancing the sashes are positioned in the vertically elongated pockets provided in the hollow jamb members 12 and 13, and may be temporarily withdrawn from such pockets through apertures 72 in order to permit the removal of worn cords and the replacement of new ones. The apertures 72 are located in the jambs 75 behind the guide strips 53, and are normally closed by plates 73 which lie flush with the jambs. Each of the plates is held in position by means of an offset tongue 74 on the back thereof which hooks behind a strip 75 80 secured to the back of the jamb. The strip 75 extends below the upper edge of the aperture 72 in the jamb, and the portion of the plate 73 opposite the tongue 74 also fits against the strip. After the upper end of the plate 73 has been thus positioned against the strip 75, the lower end, which may be slightly beveled, is swung into place over the lower edge of the aperture 72, and is held in such position by a screw 76 which 85 enters a threaded aperture in a strip 77 secured to the back of the jamb and extending upwardly beyond the lower edge of the opening therein. It will be appreciated that the construction and mounting of the cover 90 plate 73 permits the weights to be readily withdrawn from the pocket in the jamb upon removal of the single screw 76.

I claim:

1. In a metallic window construction, the 100 combination with a frame, of a sash including a muntin bar comprising two channel strips between which the margins of two adjoining glass panes are adapted to be positioned by a suitable filler, and two strips 105 which are positioned in the channel strips for closing off the channels at points just inwardly of the edges thereof, said second mentioned strips having attaching portions which are bent into contiguity with the channels inwardly of the edges thereof and welded thereto.

2. In a metallic window construction, the 110 combination with a frame, of a sash including a muntin bar comprising two channel strips between which the margins of two adjoining glass panes are adapted to be positioned by a suitable filler, two strips which are positioned in the channel strips for closing off the channels, and means inwardly of the edges of the first and second mentioned strips for connecting such strips to each other.

3. In a metallic window construction, the 120 combination with a frame, of a sash including a muntin bar comprising two channel strips between which the margins of two adjoining glass panes are adapted to be positioned by a suitable filler, and two strips 125 which are positioned in the channel strips

in generally spaced relation to the backs thereof and have positioning portions attached to such backs.

4. In a metallic window construction, the combination with a frame, of a sash including a muntin bar comprising two channel strips, two substantially flat strips positioned in the channel strips with the edges thereof just inwardly of the edges of the channel strips, and tongues punched in the flat strips and offset toward the channel strips at intervals longitudinally thereof for fixed association with the backs of the same.

5. In a metallic window construction, the combination with a frame, of a sash including a muntin bar comprising a channel strip adapted to be fixedly associated at its ends with other members of the sash, a substantially flat strip positioned in the channel strip with the edges thereof just inwardly of the edges of the channel strip, tongues punched in the flat strip and offset toward the channel strip at intervals longitudinally thereof for welded association with the backs of the same, another channel strip adapted to be detachably assembled with the first mentioned channel strip in spaced relation thereto, another substantially flat strip similarly positioned in and attached to the second mentioned channel strip, and assembling

screws passing through aligned apertures in the second mentioned channel and flat strips and engaging in threaded apertures in the first mentioned flat strip.

6. In a metallic window construction, the combination with a frame, of a sash including a muntin bar comprising a channel strip adapted to be fixedly associated at its ends with other members of the sash, a substantially flat strip positioned in the channel strip with the edges thereof just inwardly of the edges of the channel strip, tongues punched in the flat strip and offset toward the channel strip at intervals longitudinally thereof for welded association with the backs of the same, another channel strip adapted to be detachably assembled with the first mentioned channel strip in spaced relation thereto, another substantially flat strip similarly positioned in and attached to the second mentioned channel strip, and assembling screws passing through aligned apertures in the second mentioned channel and flat strips and engaging in threaded apertures in the first mentioned flat strip, said first and second mentioned flat strips being respectively of relatively heavy and light gauge.

In testimony whereof I have hereunto signed my name.

THOMAS P. SHEAN.
